A. KISTLER

BROODER

Filed May 22, 1926

Inventor
Anna Kistler
By Clarence O'Brien
Attorney

UNITED STATES PATENT OFFICE.

ANNA KISTLER, OF ROSELAND, NEBRASKA.

BROODER.

Application filed May 22, 1926. Serial No. 111,016.

This invention relates to an improved brooder or hover such as is provided for housing small chicks for protecting the same from the elements.

5 The invention, however, has more specific reference to an attachment for a conventional hover which permits the area of the latter to be increased beyond its normal size for housing a greater number of chickens in

10 a less crowded condition.

Briefly, the invention has reference to a curtain which is adjustably and detachably connected to the lower portion of the hover to entirely close the space between the bottom of the metal hood and the ground or to permit it to be varied to suit the conditions met.

20 My principal object is to provide a simple and inexpensive attachment which may be used in association with conventional marketed brooders without requiring alteration and serving to decidedly enhance the utility of the marketed products.

25 Other objects and advantages of the invention will become apparent from the following description and drawings.

In the accompanying drawing forming a part of this application and in which like numerals are employed to designate like parts 30 throughout the same:

Figure 1 is a top plan view with portions broken away to disclose the details more plainly.

Figure 2 is a central vertical section 35 through the same.

In the drawing the reference character 1 designates generally a conventional brooder which includes the usual frusto-conical hood 2 which is ordinarily of light weight metal, and 3 represents a heater such as is usually installed beneath the hood.

40 The invention comprises a plurality of attaching arms 4 having their inner end portions 5 riveted or otherwise permanently secured to the lower edge portion of the hood as shown in the drawing. The outer ends of these arms project beyond the edge of the hood and are provided with the eyes 6 in which a wire hoop or ring 7 is fastened. 45 Obviously the arms are arranged at circumferentially spaced points so as to properly support the wire. In addition, the device includes a flexible curtain 8 of appropriate material such as will withstand the abuse of the

elements. This curtain is properly reinforced at its bottom as indicated at 9 and its opposite upper edge is formed with a pocket 10 for reception of a flexible drawing string 11.

55 The curtain is placed in position in a manner to permit the upper half to span the space between the peripheral edge of the hood and the wire supporting ring 7. This is accomplished by drawing the string 11 sufficiently tight and tying the ends in a bow 60 as shown. Moreover, the lower half is permitted to depend or hang down as shown, and it is obvious that by adjusting the drawing string, it may be permitted to hang low or high as desired. Thus, in bad weather, it 65 can be permitted to hang and come in contact with the ground or floor, as the case may be, and in more favorable weather it may be raised slightly by drawing the string in an obvious manner.

70 The use and advantages of an invention of this kind will be plain to those familiar with brooders and the invention is of such simple nature that a more detailed description is hardly necessary. Moreover, the alleged novelty of the improvement is pointed out specifically in the appended claims.

75 Minor changes coming within the field of invention claimed may be resorted to if desired.

80 Having thus described the invention, what I claim as new and desire to secure by Letters Patent is:—

1. An attachment for a brooder of the class described comprising a plurality of attaching arms adapted to be connected at their inner ends with the lower edge portion of the hood of the brooder, the outer end portions of said arms being adapted to project outwardly beyond the lower edge portion in a substantially horizontal plane, said outer ends terminating in eyes, a ring supported from said eyes, and a flexible curtain provided at its top with a pocket in which a drawing string is located and having its lower edge portion reinforced, said curtain being adapted to cover the space between the ring and hood and to have its lower end portion hanging down from said ring to form an enclosure for the hood. 90

95 100 105 2. In a brooder of the class described, in combination, a conical hood, a curtain suspension ring adapted to surround the lower

edge portion of the hood in radially spaced relation, means for supporting said ring in a plane with said lower edge portion, and a flexible curtain covering the space between the ring and edge of the hood, and depending from said ring, said curtain being provided at its top with a drawing string, where-

by upon gathering the same, it will be caused to ride upwardly on the conical surface of the hood to regulate the space between the bottom edge of the curtain and the ground.

In testimony whereof I affix my signature.

ANNA KISTLER.
